UNITED STATES PATENT OFFICE.

LEANDER H. LA CHANCE, OF CHICAGO, ILLINOIS, ASSIGNOR TO CHICAGO FLEXIBLE SHAFT COMPANY, OF CHICAGO, ILLINOIS, A CORPORATION OF ILLINOIS.

HAND-CLIPPER.

1,164,532.

Specification of Letters Patent. Patented Dec. 14, 1915.

Application filed October 13, 1913. Serial No. 784,761.

To all whom it may concern:

Be it known that I, LEANDER H. LA CHANCE, a citizen of the United States, residing at Chicago, in the county of Cook and State of Illinois, have invented new and useful Improvements in Hand-Clippers, of which the following is a specification, reference being had to the accompanying drawings, forming a part thereof.

10 The purpose of this invention is to provide an improved and simplified form of knife for use in a hand-operated clipper of the type known as a "comb" shear.

It consists of the features and elements 15 described and shown in the drawings as indicated by the claims.

In the drawings:—Figure 1 is a top plan view of a hand clipper embodying this invention. Fig. 2 is a section taken as indicated at line 2—2 on Fig. 1. Fig. 3 is a detail perspective view of the knife. Fig. 4 is a sectional detail of the knife taken as indicated at line 4—4 on Fig. 1. Fig. 5 is a sectional detail of a modified form of the 25 invention.

The clipper to which this invention relates is of a type in which the elements are reduced to their simplest terms. The two handles, A¹ and A², are formed as integral 30 portions of the spring, A, by which they are yieldingly held apart. The handle, A¹, carries rigidly the cutter comb, B, and the handle, A², engages the knife, C, for the purpose of oscillating the latter over the 35 comb in the cutting operation the spring, A, serving to return the parts to the relative positions illustrated in Fig. 1. Stop pins, D, D, are fixed on the comb member, B, to limit the stroke of the knife, C. To 40 render the clipper effective in operation, it will be understood that the knife, C, must be pressed firmly against the comb, B, and to accomplish this the handle, A², which carries said knife is initially sprung toward the comb, B, so as to exert a pressure in this 45 direction for holding the knife, C, in contact with the comb. For the sake of simplicity and cheapness of manufacture the knife, C, is connected with its operating 50 handle, A², merely by the engagement of the latter with a recess or notch in the upper face of the knife, the spring pressure of the handle, A², in the direction of the comb, B, serving to maintain such engagement. As 55 illustrated in the drawing the knife, C, is

formed of flat stock bent into a hump, C¹, intermediate between the two-edged cutting end, C², and the heel, C³, of the knife, and this hump, C¹, is notched at C⁴, to receive the end of the handle, A². To retain the knife, C, against longitudinal movement along the handle, A², the latter is formed with a stop shoulder, A²¹, engaging the rear face of the hump, C¹, and the extreme end of said handle is bent at A²², forming a second shoulder 60 engaging the forward face of the hump. This latter construction is preferred in that it furnishes the necessary stop shoulder with a minimum protrusion of the end of the handle, A², thus lessening its liability to become caught in the hair during use of the tool. By virtue of the simplicity of this engagement between the handle, A² and the knife, C, the removal of the latter for sharpening or replacement is greatly facilitated, 65 and correctness of adjustment is insured once for all in the manufacture of the tool. To add to the convenience of the clipper in use the handles, A¹ and A², are provided, respectively, with a thumb piece, A¹⁰, and 70 finger notches, A²⁰, as illustrated in Figs. 1 and 2.

Fig. 5 illustrates a modification in the form of the handle, A², for engaging the knife, C. Instead of bending the extreme 75 end as at A²², in Fig. 4, this end is cut off short so as to terminate flush with the forward face of the hump, C¹, and the stop shoulders which prevent longitudinal movement of the knife along the handle constitute a projection extending downwardly 80 from the handle inside the hump, C¹, abutting the respective inner walls of the hump at A²³ and A²⁴.

I claim:—

1. In a comb clipper comprising two spring-connected handles, a comb rigidly secured to one of them, the other being adapted to vibrate toward and from the first; a knife carried by the second handle having 100 in its upper side an upwardly open recess presenting lateral walls for engagement of the vibrating handle, the end of said handle being normally sprung toward the comb for engagement with the recess of the knife 105 to vibrate the latter and press it toward the comb.

2. In a comb clipper comprising two spring-connected handles, a comb rigidly secured to one of them and a knife carried by 110

the other, the knife having intermediate between its point and heel, a transversely extending upraise, said upraise having a notch extending entirely across it longitudinally of the knife and handle, and the end of the handle being sprung toward the comb and lodged in the notch of the knife, said handle being provided with abutments arranged to stop the knife against longitudinal movement on the handle.

3. In a comb clipper comprising two spring-connected handles, a comb rigidly secured to one of them and a knife carried by the other, said knife having intermediate between its point and heel, a transversely extending upraise having an upwardly open notch extending across it longitudinally of the knife, the end of the handle being sprung toward the comb and lodged in the notch of the knife, said handle being formed with a shoulder abutting the rear face of the upraise of the knife, and the extreme end of the handle being bent to engage the forward face of said up-raise for stopping the knife against longitudinal movement on the handle.

4. In a comb clipper comprising two spring-connected handles, a comb rigidly secured to one of them and a knife carried by the other, said knife being formed of flat stock with a transversely and upwardly ex-

tending hump bent in it intermediate between the point and the heel, the top of said hump being slotted to form a notch and the end of the handle being sprung toward the comb to engage said notch, and means adapted to stop the knife against movement longitudinally on the handle.

5. In a comb clipper comprising two spring-connected handles, a comb rigidly secured to one of them and a knife carried by the other, said knife being formed of flat stock with a transversely and upwardly extending hump or bend in it intermediate between the point and the heel, the top of the hump being slotted to form a notch and the end of the handle being normally sprung toward the comb and adapted to engage said notch, the engaging end of the handle having two shoulders which engage respectively in front of and behind the two walls of the hump for stopping the knife against movement longitudinally with respect to said engaging end portion of the handle.

In testimony whereof I have hereunto set my hand at Chicago, Illinois, this 9th day of October, 1913.

LEANDER H. LA CHANCE.
